UNITED STATES PATENT OFFICE.

WALTHER WILLENBRUCH, OF NEW YORK, N. Y., ASSIGNOR TO WESTERN ELECTRIC COMPANY, INCORPORATED, OF NEW YORK, N. Y., A CORPORATION OF NEW YORK.

ELECTROMAGNETIC SWITCHING DEVICE.

1,330,507.

Specification of Letters Patent. Patented Feb. 10, 1920.

Application filed December 30, 1916. Serial No. 139,877.

To all whom it may concern:

Be it known that I, WALTHER WILLENBRUCH, a subject of the Emperor of Germany, residing at New York, in the county 5 of Bronx and State of New York, have invented certain new and useful Improvements in Electromagnetic Switching Devices, of which the following is a full, clear, concise, and exact description.

10 This invention relates to electromagnetic switching devices, its object being to provide an electromagnetic switching device or relay which is slow in releasing, and which is simple in construction and positive in action.

15 In accordance with one feature of this invention, an electromagnetic relay is constructed with a secondary source of current in shunt with a main energizing element. In the preferred embodiment an electrolytic 20 cell and a regulating resistance, connected in series therewith, are connected in shunt of an energizing winding of the relay or a portion of such winding.

The nature of this invention will be more 25 clearly seen by reference to the drawing, in which Figure 1 shows schematically one embodiment of the invention suitable for high voltage relays; and Fig. 2 another, suitable for low voltage service.

30 Corresponding parts in the two figures of the drawing are designated by the same reference symbols.

Referring now to the drawing, 5 is an electromagnetic relay comprising a core 8, an 35 energizing winding 9, an armature 10 and a contact 11. The armature 10 is normally out of engagement with contact 11, but this arrangement is not essential to this invention, since contact 11 could as well be positioned that armature 10 would normally be 40 in engagement therewith. The relay 5 is then shown connected in a main circuit with a battery 12 and a key 13. In shunt with a portion of the winding 9 of relay 5 in Fig. 1, 45 and all of the winding 9 in Fig. 2, is connected an electrolytic cell 6 and a regulating resistance 7.

The electrolytic cell 6 may be of any well-known type which is capable of reacting 50 to an electric current so as to produce a counter-electromotive force for a finite period of time after the discontinuance of the charging current. The preferred construction, however, is shown in the drawing, in 55 which two platinum electrodes 14, 14 are

sealed into a glass container 15, which is partly filled with an electrolyte 16 of dilute sulfuric acid.

It is believed that the invention will be clearly understood from a description of the 60 operation of the schemes, shown in the drawing, and it will be so described.

It will be assumed that the relay 5 has been actuated by the closure of the main circuit at the key 13, so that the armature 10 65 is in its attracted position and in engagement with contact 11. Under these conditions a certain value of current is flowing through the winding 9, and there is a corresponding difference of potential between the 70 terminal points 17 and 18 of the shunt including the electrolytic cell 6 and the regulating resistance 7. By the proper location of the terminal point 17, by the suitable construction of the electrolytic cell 6, or by the 75 right adjustment of the resistance 7, the corresponding potential across the terminals of the electrolytic cell 6 can be made of such a value that a charging current will pass between the electrodes 14, 14. Due to this current, the cell will be polarized and will be maintained in this condition as long as the main circuit remains closed.

Assuming now that the main circuit is opened at key 13, the relay 5 ordinarily 85 would become immediately deenergized and the armature 10 would at once return to its normal position, but, due to the coöperation of the elements in accordance with this invention, the polarization of the electrodes 14, 90 14, hereinbefore mentioned, causes the electrolytic cell to furnish a reverse flow of current, which passes through the portion of the winding between terminal points 17 and 18 in the same direction as the main energizing current. This current will continue 95 for a finite period of time, and, so long as it is at least as large as the minimum current necessary to hold the armature 10 in attracted position, the relay will not release. 100 Depending upon the construction of the electrolytic cell 6, the value of resistance 7, the portion of the winding between terminal points 17 and 18, and the adjustment of the relay, the time required for the discharge 105 current to fall below the minimum holding value of current for the relay will be determined.

In the preferred construction of the electrolytic cell, as shown in the drawing and 110

hereinbefore described, the amount of the discharge current due to the polarization of the platinum electrodes is of a fairly fixed value, regardless of the length of time that 5 the charging voltage is applied. Therefore, when such a cell is combined in a circuit with a given relay and regulating resistance, the time of release of that relay will be fixed and uniform,—a necessary condition for satisfactory operation.

What is claimed is:

1. In combination, a relay, an energizing winding therefor, a source of energizing current adapted to be associated with and 15 disassociated from the winding, and a polarization cell permanently shunting a portion of the winding to store energy upon the association of the source with the winding and to dissipate such energy through such 20 portion, thereby delaying the deenergization thereof for a time interval determined by the amount of energy stored.
2. In combination, a relay, an energizing winding therefor, a source of energizing 25 current adapted to be associated with and disassociated from the winding, and a polarization cell to store energy for a predetermined time upon the association of the source with the winding and to dissipate 30 such energy through the winding upon the subsequent disassociation of the source there-

from to delay the deenergization thereof for a definite period independent of the extension of the association period beyond the predetermined time.

35

3. In combination, a relay, an energizing winding therefor, a source of energizing current adapted to be associated with or disassociated from the winding, and a polarization cell associated with the winding 40 adapted to store energy upon the association of the source with the winding and to dissipate such energy through the winding upon the subsequent disassociation of the source therefrom to delay the deenergization 45 thereof for a definite period determined by the amount of energy stored.

40

4. In combination, a relay, an energizing winding therefor, a source of energizing current adapted to be associated with and 50 disassociated from the winding, and a polarization cell associated with the winding to store energy upon the association of the source with the winding and to dissipate such energy through the winding upon the 55 disassociation of the source from the winding to delay the deenergization thereof.

In witness whereof, I hereunto subscribe my name this 29th day of December A. D., 1916.

WALTHER WILLENBRUCH.
